CLAIM

The ornamental design for an ice skate, as shown and described.

DESCRIPTION

FIG. 1 is a bottom left side perspective view of the left ice skate of our invention;

FIG. 2 is a bottom view thereof;

FIG. 3 is a left side elevational view thereof;

FIG. 4 is a right side elevational view thereof;

FIG. 5 is a front view thereof; and,

FIG. 6 is a rear view thereof.

The right ice skate is a mirror image of the ice skate shown.
